Primary Examiner — Samantha Wood

(57) CLAIM

The ornamental design for a ring for a wall faucet, as shown and described.

DESCRIPTION

FIG. 1 is a perspective view of a ring for a wall faucet, showing our new design.

FIG. 2 is a front view of the ring for a wall faucet of FIG. 1.

FIG. 3 is a back view of the ring for a wall faucet of FIG. 1.

FIG. 4 is a right side view of the ring for a wall faucet of FIG. 1.

FIG. 5 is a left side view of the ring for a wall faucet of FIG. 1.

FIG. 6 is a top view of the ring for a wall faucet of FIG. 1; and,

FIG. 7 is a bottom view of the ring for a wall faucet of FIG. 1.

The broken lines depict portions of the ring for a wall faucet that form no part of the claimed design and the dash-dot lines define the boundaries of the ring for a wall faucet that form no part of the claimed design.

1 Claim, 7 Drawing Sheets
